HERMANN V. FENGLER, OF PHILADELPHIA, PENNSYLVANIA, ASSIGNOR TO REMINGTON TYPEWRITER COMPANY, OF ILION, NEW YORK, A CORPORATION OF NEW YORK.

TYPE-WRITING MACHINE.

1,241,101.

Specification of Letters Patent. Patented Sept. 25, 1917.

Application filed July 24, 1914. Serial No. 852,814.

To all whom it may concern:

Be it known that I, HERMANN V. FENGLER, citizen of the United States, and resident of Philadelphia, in the county of Philadelphia and State of Pennsylvania, have invented certain new and useful Improvements in Type-Writing Machines, of which the following is a specification.

My present invention relates to line spacing mechanism for typewriting machines, and its principal object is to provide new and improved mechanism of the character specified, and more especially such mechanism wherein a wider variation in the spacing than is usual may be obtained.

To the above and other ends my invention consists in the features of construction, combinations of devices, and arrangements of parts hereinafter described and particularly pointed out in the claims.

In the accompanying drawings which illustrate the preferred form of the invention,

Figure 1 is a fragmentary plan view, partly in section, of the carriage of a typewriting machine embodying my invention.

Fig. 2 is a transverse sectional view taken on the plane indicated by the dotted line $x-x$ in Fig. 1 and looking in the direction of the arrow at said line.

Fig. 3 is an enlarged fragmentary horizontal sectional view taken on a plane indicated by the dotted line $y-y$, in Fig. 2 and looking downward.

Fig. 4 is an enlarged fragmentary transverse sectional view taken on a plane indicated by the dotted line $z-z$, in Fig. 1 and looking in the direction of the arrow at said line.

Fig. 5 is a detail face view of an element hereinafter referred to as a ratchet wheel or regulator.

The carriage, shown in Figs. 1, 2 and 3, is rectangular, comprising front and rear bars 1 and 2 connected by end bars 3 and 4, and is suitably mounted in a typewriting machine of any desired construction. On the carriage is a rotary platen comprising a wooden core 5 and an outer sheath 6 of rubber, said platen being supported on an axle which may comprise two relatively movable parts 7 and 8, said axle bearing at the right in the end bar 4 and being provided outside

said end bar with a finger wheel 9. At the left outside the platen the axle is provided with a beveled gear wheel 10 having a hub portion 11 which is riveted or otherwise secured to the axle, said hub portion bearing in an extension 12 projecting rearward from the front bar 1. The right-hand end of the platen may be provided with a suitable platen head 13 having a hub formed with a slot 13a which is slidably engaged by a pin 8a on the shaft 8. At the left the platen has secured to it as by wood screws 14 a platen head 15 which is provided with crown gear teeth 16. The inner end of the hub 11 abuts said head 15, said gear teeth providing a gear wheel of a diameter substantially equal to that of the platen and rigidly connected thereto. The construction is such that the platen axle 7-8 may be turned freely in its bearings 12 and 4 to cause rotations of the platen 5, 6. Also said axle may be moved longitudinally toward the left in its bearings for a purpose hereinafter described and when thus moved may be retained in abnormal position by latching devices comprising a latch 17 provided with a finger piece 18 and pivoted at 19 on the end bar 4, said latch being adapted to coöperate with a flange 20 fixed to the platen axle.

Line spacing movements are communicated to the platen by devices comprising a small roll 21 of rubber, compressed fiber or other suitable composition, said roll being adapted to coöperate frictionally with the outer face of the platen head 15. Said platen head may be faced with a suitable material, or roughened or otherwise prepared in the way found best to afford effective frictional contact with the roll 21 with a minimum of wear. Said roll is fixed on a sleeve 22 which bears loosely on a shouldered portion of a headed screw 23, said screw being threaded into a bracket 24 secured to the rear bar 2 by screws 25. A nut 26 locks the screw 23 on said bracket. Secured to the sleeve 22 in rear of the roll 21 so that it is rigid therewith is a pinion 27 of slightly smaller diameter than the roll 21, the difference in the drawing being somewhat exaggerated. Said pinion remains constantly in mesh with the crown gear 16, the purpose of the gear and pinion connection being to prevent slipping or

overthrow taking place between the roll 21 and the platen head 15 under a violent or jerky line spacing operation.

Motion is communicated to the roll 21 by 5 an actuating member, disk or regulator 28. Said disk is preferably composed of two parts 29 and 30 secured together face to face by screws 31. The inner face of the inside part 30 is formed with two diametrical grooves 32 at right angles to each other, each half of each groove being adapted during the course of a succession of line spacing operations to receive the roll 21 when the parts are at rest. As shown in Fig. 5 10 the screws 31 are preferably arranged equidistant from each other and from the intervening grooves 32 with which they alternate. The outside part 29 is bored out to receive a headed shoulder screw 33, the 15 head 34 of said screw being received in a counter-sink 35 in the inner face of said part 29. The construction is such that when the parts 29 and 30 are secured together by the screws 31, said parts turn together as 20 a single piece on the screw 33. The depth of the counter-sink 35 is such as to afford lost motion of the disk 28 sufficient to permit it to be disengaged or separated from the roll 21 when said disk is pushed leftward along the screw 33, this movement being accomplished by the gear wheel 10 when the axle 7-8 is pushed leftward. The outer end of the screw 33 is reduced and threaded and is screwed into a threaded 25 30 opening in a lug 36 formed on a traveling support, carrier or bracket 37 which is arranged inside the end bar 3 and is formed at its forward end portion with a screw thread 38. The threaded or screw portion 38 bears 35 loosely in detachable journals 39 and 40. Screws 41 fix the journal 39 to the end bar 3, and the journal 40 is secured by screws 42 to the front bar 1. Between the journals 40 and arranged in a bight 3^a in the end bar 45 3 is a beveled gear wheel 43. Said gear wheel is of somewhat larger diameter than the gear wheel 10 which is adapted to mesh with it, although the two gear wheels are normally separated. The gear 43 is provided with a hub portion 44 which is formed with an internal thread that is engaged by the screw 38, and its length is such 50 that it is confined loosely between the journals 39 and 40 so that endwise movement of 55 the gear wheel 43 is prevented, although it may turn freely on and relatively to the screw 38. The construction is such that when the gear wheel 10 is moved leftward to mesh with the gear wheel 43 and subsequently rotated by turning movements applied to the finger wheel 9, rotary movements will be communicated to the gear wheel 43 which will co-act with the screw 38 to transmit lengthwise movements transversely of the platen to said screw and to

the member or carrier 37 of which it is a part. The leftward movement of the gear wheel 10 above referred to is also effective to push the disk 28 leftward so that its inner face will be carried out of engagement 70 with the periphery of the roll 21. This disengaging movement is resisted by a spring 45 coiled around the shouldered portion of the screw 33 and confined between said disk and a washer 46 that abuts against the lug 75 36. When leftward pressure is removed from said disk the spring 45 is effective to restore it to coöperative engagement with the roll 21. Said roll is preferably slightly compressed to better transmit motion, and 80 also that it may expand into one or another of the grooves 32 when at rest, insuring that the parts and platen are held or detained in adjusted positions. The rear portion of the carrier 37 is formed with a rightward extension 37^a terminating in an upwardly and forwardly curved end portion 37^b provided with a slot or kerf which receives and guides a line spacing pawl 47. This pawl is arranged in the fore and aft plane of the 90 disk 28 and it terminates at its rear or lower end in a tooth 48 which is adapted to coöperate with ratchet teeth 49 formed on the periphery of said disk, which in effect is a ratchet wheel. There are four of said 95 ratchet teeth in the present instance. Said pawl is provided with lateral stop pins 50 and 51 which are adapted to coöperate respectively with the top and bottom of the end portion 37^b to limit positively the 100 strokes or actuating movements of said pawl and the actuator or lever by which it is controlled and consequent turning movements of said disk or ratchet wheel. The pawl is supported on and actuated by a line 105 spacing lever 52 with which it is pivotally connected at 53, said lever being pivoted on a shoulder screw 54 secured in a lug 55 on the carrier 37. A washer 56 is arranged on said screw to the left of the lever 52, which is confined between said washer and the head of the screw 54. The pivot or screw 53 is threaded into a lug 52^a on said lever, said lug extending laterally rightward, with the result that the pawl is offset far enough 115 to bring it into the plane of the ratchet wheel 28. The lever 52 terminates at its free end in a portion that is suitably shaped to accommodate the finger of the operator. 120 Normally a hand operated latch or locking device 57 pivoted at 58 to the front bar 1 is maintained in engagement with the teeth of the gear wheel 43 by a spring 59. This locks the gear wheel 43 against turning movements and so fixes the position of 125 the carrier 37 and of the pawl and ratchet devices and all of the other parts supported thereon and bodily movable therewith. By pushing toward the right the finger piece 57^a with which said latch is provided 130

spring 59 is overcome and the gear wheel 43 is free to be turned to readjust the carrier 37 and the parts mounted thereon. To facilitate such adjustment a scale, indicating marks or devices 60 is formed on the upper face of the end bar 3. Coöoperating with this scale is a movable indicating device mounted on the carrier. In the present instance this movable indicating device may be the lower edge of a guide strap or band 61 secured by screws 62 to the carrier 37 near its rear end, said strap being bent over the top, outer side and under side of the end bar 3, forming a U-guide which promotes the rigidity of the carrier 37 and steadies it both when at rest and during its movements of adjustment.

Normally the line spacing lever 52 is in its forward position as shown by dotted lines in Fig. 2. When a line spacing operation is effected the lever is first pushed rearward to the full line position of Fig. 2 and the pawl 47 is guided downward and forward by the guide end 37^b until arrested by the stop pin 50 contacting with the top of said end 37^b, at which time the pawl tooth 48 will be engaged with the ratchet tooth 49 at the underside of the disk 28. Thereupon the lever 52 is pulled forward from the full line to the dotted line position in Fig. 2, the movement continuing until the parts are arrested by the contact of the stop pin 51 with the end or stop device 37^b. This last movement of the lever acting through the pawl or actuating device communicates a quarter turn to the disk or driving member 28 sufficient to cause one of the grooves 32 in said disk to disengage from the roll 21 and the next groove 32 in rear of the previously engaged groove to engage with said roll. During this quarter turn of the disk it will operate frictionally on the roll 21, turning said roll on its axis and causing it in turn to communicate turning movements to the platen. The pawl engages with the wheel or disk 28 from the beginning of the actuating stroke and continues so engaged until the end of the stroke. It will be understood that the extent of turning movement thus communicated to the platen will depend on the setting of the disk 28 with relationship to the roll 21. This setting may be varied so that a greater or less extent of rotary movement will be communicated to the platen, according as the roll 21 engages with the disk 28 farther from or nearer to the axis of said disk. Assuming that the parts are set as in Figs. 2 and 3, they are so proportioned and arranged that a line spacing movement communicated to the lever 52 will transmit to the platen a turning movement of an extent known commonly in the art as "double spacing." If it is desired to vary this turning movement of the platen and to obtain, say, single spacing,

the operator first pushes the finger wheel 9 inward toward the left, thus moving the axle or shaft 7—8 longitudinally leftward, and locks the parts against accidental return by swinging the latch 17 into engagement with the flange 20. The resulting leftward movement of the gear wheel 10 causes it to mesh with the gear wheel 43 and at the same time acting against the disk 28 to disengage the same from the roll 21. Next the operator unlocks the gear wheel 43 by manipulating the finger piece 57^a of the latch 57 and thereafter turns the finger wheel 9, communicating rotary movements to the gear wheel 10 and through the intermeshing gear wheel 43 to the screw 38 and carrier 37 of which said screw is a part. As a result the carrier is moved rearward transversely of the platen and this rearward movement results in a rearward bodily movement of the disk 28 which is carried by said carrier. Such movement is continued until the lower edge of the strap 61 is brought into register with the indicating mark "1" on the scale 60. Thereupon the latch 57 is released, locking or setting the disk and associate parts in the new position, and the latch 17 is swung leftward, releasing the platen axle and the gear wheel 10 allowing the disk 28 to be restored to be reengaged with the roll 21. As a result of the resetting of said disk such reengagement will be nearer to the axis of said disk; and in effect there has been a relative movement of the friction wheels 28 and 21 radial of the wheel 28. Consequently, though the line spacing actuations of the lever 52 and consequent turning movements of said disk or wheel 28 are constant, the resulting movement transmitted to the roll 21 and through it to the platen will be less, and the platen will receive only a single unit of line space movement. By turning the finger wheel 9 without pushing it inward the platen may be turned slightly either forward or backward to give fractional spacing below or above the writing line.

It will be seen that by the present invention means is afforded for communicating a constant actuating movement to the line spacing lever and for varying the resulting line spacing movement of the platen, this being accomplished by means which do not include the ordinary devices for varying the engagement between the pawl and ratchet members of the line spacing train. It will further be understood that the invention provides for obtaining a wide variation in the extents of line spacing movement, this being because of the fact that I am not restricted to such variations as are due to differences between teeth of a ratchet wheel as is usually the case. For example, the wheel 28 may be set in a plurality of different positions between "1" and "2" on the scale thus

obtaining spacing of extents varying between single and double spacing.

It is to be understood of course that the principles of the present invention may be

- 5 adapted to various styles of typewriting machines including most if not all of those in common use, and that various ways of putting said principles into effect may be employed without departing from the scope of
10 the invention; also that changes in the present constructions may be made without departing from the invention. For example, instead of first pushing the lever 52 rearward and then pulling it back again for actuating the line spacing mechanism, the said lever may be normally maintained in the full line position of Fig. 2 by a spring of ordinary construction so that it will only be necessary to pull said lever forward to activate the line spacing mechanism, after which on releasing the lever it will be restored to the full line position by its spring.

It will be observed that by my present invention there is provided a line spacing 25 driving member for driving the platen in combination with means for driving said member which engages with it from the beginning of the actuating stroke, the construction being such that the platen is caused

30 to turn as soon as movement of said driving member begins; that the driving member, in the present instance a line spacing ratchet wheel, has a constant or unvarying extent of line spacing movement; that connections between said ratchet wheel and said platen

35 are provided in combination with means for varying the relationship of said connection to vary the line spacing movement of the platen; that the line spacing mechanism

40 comprises two coöperating rotary members combined with means for varying their normal relationship to vary the extent of movement communicated by one of them to the other; that said members, in the present in-

45 stance, are frictional wheels or rollers one having a groove in one of its flat faces to receive the rounded or peripheral portions of the other or second roller; that said groove in the present instance is straight and that

50 there are two of these grooves, at right angles to each other; that said second roller engages successively with grooved portions of the grooved roller; that the two friction rollers are normally engaged with each

55 other so that as soon as one starts to move its movement is instantly communicated to the other; that the driven friction roll is pivotally supported and frictionally engages with the ratchet wheel and with the

60 platen; that the axis of said pivoted roll is at right angles to the axis of the platen and to said ratchet wheel; that the face of the ratchet wheel with which said pivoted roll engages is a flat surface that is rigid with

65 the platen; and that said flat surface is ro-

tary and is perpendicular to the axis about which it turns, that is, to the platen axis.

What I claim as new and desire to secure by Letters Patent, is:—

1. In a typewriting machine, the combination of a platen and line spacing devices comprising a driving member, means for driving said member engaging therewith from the beginning of the actuating stroke, the platen being caused to turn as soon as movement of said driving member begins, and means for varying the effect of said driving member, as it operates, on said platen. 70

2. In a typewriting machine, the combination of a platen and line spacing devices comprising a driving member, an actuating device for driving said member, said actuating device engaging with said driving member from the beginning of the actuating stroke, the platen being caused to turn as soon as movement of said driving member begins, and means for varying the normal relationship between said driving member and said platen to vary the extent of 80 line spacing movement. 85

3. In a typewriting machine, the combination of a platen, a line space actuator, and frictional devices operative by said actuator for line spacing said platen, the platen being caused to turn as soon as movement of said frictional devices begins, said devices being variable in their effect one on the other to vary the extent of line spacing movement of said platen. 95

4. In a typewriting machine, the combination of a platen, a line space actuator having a constant throw, and frictional devices operative by said actuator for line spacing said platen, the platen being caused to turn as soon as movement of said frictional devices begins, said devices being variable to vary the extent of line spacing movement of 100 said platen. 105

5. In a typewriting machine, the combination of a platen, a line spacing wheel, means for giving said wheel an unvarying line spacing movement, and connections between said wheel and said platen for varying the extent of line spacing movement which 115 the platen receives. 110

6. In a typewriting machine, the combination of a platen, a line spacing ratchet wheel, an actuator for giving said wheel an unvarying line spacing movement, connections between said ratchet wheel and said platen, and means for varying the relationship of said connections to vary the line spacing movement of said platen. 120

7. In a typewriting machine, the combination of a platen, two coöperating friction rollers, the face of one of said rollers coöperating with the periphery of the other, turning means operative on one of said rollers, and means for maintaining said rollers 125 130

in predetermined relationships so as to maintain the platen in adjusted positions.

8. In a typewriting machine, the combination of a platen, two friction rollers, the face of one of said rollers coöperating with the periphery of the other roller, said face being formed diametrically with a groove to receive said other roller, and turning means operative on one of said rollers.

10 9. In a typewriting machine, the combination of a platen, and line spacing mechanism therefor comprising two coöperating rotary members, and means for varying the normal relationship between said members 15 to vary the extent of movement communicated by one to the other.

10 10. In a typewriting machine, the combination of a platen, and line spacing mechanism therefor comprising two coöperating friction wheels or rollers, one having a groove in one of its flat faces to receive the rounded or peripheral portions of the other.

10 11. In a typewriting machine, the combination of a platen, line spacing mechanism 25 therefor comprising two coöperating friction wheels or rollers, one grooved to receive the other, and means for turning the grooved roller so as to cause the other roller to co-operatively engage successively with grooved 30 portions of said grooved roller.

10 12. In a typewriting machine, the combination of a platen, line spacing mechanism therefor comprising two coöperating friction wheels or rollers, one grooved to receive 35 the other, means for turning the grooved roller so as to cause the other roller to co-operatively engage successively with grooved portions of said grooved roller, and means operative on said grooved roller for varying 40 the extent of line spacing movements communicated to the platen.

10 13. In a typewriting machine, the combination of a platen, and line spacing mechanism therefor comprising two coöperating friction rollers, and means for varying the 45 relationship between said rollers to vary the extent of line spacing movement communicated to the platen, one of said friction rollers having a constant line spacing movement.

10 14. In a typewriting machine, the combination of a platen, and line spacing mechanism therefor comprising two normally engaged friction rollers, and means for setting 55 one of said rollers in varying relationship with the other to vary the extent of line spacing movement.

10 15. In a typewriting machine, the combination of a platen, and line spacing mechanism therefor comprising two coöperating rotary devices, and means for effecting a 60 relative radial adjustment between said devices to vary the line spacing movement.

10 16. In a typewriting machine, the combination of a platen, and line spacing mecha-

nism therefor comprising two coöperating friction wheels, and means for effecting a relative shifting of one of said wheels radially of the other.

17. In a typewriting machine, the combination of a platen, and line spacing mechanism therefor comprising a ratchet wheel, actuating means therefor, and a pivoted friction roll engaging with said ratchet wheel and with said platen, the axis of said roll being at right angles to the axes of both said ratchet wheel and said platen.

18. In a typewriting machine, the combination of a platen, and line spacing mechanism therefor comprising a ratchet wheel, actuating means therefor, and a friction roll engaging with said ratchet wheel and with said platen, said ratchet wheel being provided with grooves to accommodate said friction roll.

19. In a typewriting machine, the combination of a platen, and line spacing mechanism therefor comprising a pivoted friction roll engaging with a flat surface rigid with the platen, means for actuating said roll, and connections between said platen and said roll to prevent slipping.

20. In a typewriting machine, the combination of a platen, and line spacing mechanism therefor comprising a friction roll engaging with the platen, means for actuating said roll, and connections between said platen and said roll to prevent slipping, said connections comprising a pinion rigid with said roll and a gear rigid with said platen.

21. In a typewriting machine, the combination of a platen, and line spacing mechanism therefor comprising a line space wheel, and means for varying the setting of said wheel transversely of the platen to vary the line spacing movement of said platen.

22. In a typewriting machine, the combination of a platen, line spacing mechanism therefor comprising pawl and ratchet devices, and means for bodily moving said devices to vary their position so as to vary the extent of line-space turning movement of said platen.

23. In a typewriting machine, the combination of a platen, and line spacing mechanism therefor comprising a line spacing ratchet wheel having a constant throw, means for moving said ratchet wheel bodily transversely of the platen, and means for fixing the bodily position of said ratchet wheel after readjustment.

24. In a typewriting machine, the combination of a platen, and line spacing mechanism therefor comprising a line spacing ratchet wheel, means for moving said ratchet wheel bodily transversely of the platen, and means comprising a hand controlled detent for fixing the bodily position of said ratchet wheel.

25. In a typewriting machine, the combination of a platen frame; a platen thereon; and line spacing mechanism comprising a line spacing wheel, and means for varying 5 the relationship of said wheel with said platen, said means comprising a carrier on which said wheel is rotatably mounted, said carrier being mounted on said platen frame, and means for variably setting said carrier 10 on said platen frame.

26. In a typewriting machine, the combination of a platen frame; a platen thereon; and line spacing mechanism comprising a line spacing wheel, and means for varying 15 the relationship of said wheel with said platen, said means comprising a carrier on which said wheel is rotatably mounted, said carrier being mounted on said platen frame, and means for variably setting said carrier 20 on said platen frame, said setting means comprising a screw on said carrier, and a gear wheel engaging said screw and having a fixed path of rotation.

27. In a typewriting machine, the combination of a platen, a platen frame, line spacing mechanism comprising a regulator, a carrier for said regulator mounted on said platen frame, means operative by turning the platen for moving said carrier and adjusting said regulator, and a scale on the platen frame for coöperation with said carrier.

28. In a typewriting machine, the combination of a platen, two co-acting line spacing wheels, hand operated means for turning 35 one of said wheels to transmit line spacing movement through the other of said wheels to the platen, and other means for turning the platen to vary the normal relationship between said wheels.

29. In a typewriting machine, the combination of a platen, a train of devices effective when actuated to turn the platen for

line spacing, said train comprising a regulator, said regulator being bodily movable 45 for varying the line space movement, and connections between said regulator and said platen, turning movements of said platen being transmitted to said connections to bodily move said regulator. 50

30. In a typewriting machine, the combination of a rotary platen, a line spacing wheel normally connected with the platen, and a train of devices for variably setting 55 said line spacing wheel, said train comprising a device mounted and controlled by the platen axle, said device being also operative to temporarily disconnect said wheel from said platen during adjusting operations.

31. In a typewriting machine, the combination of a platen, pawl and ratchet devices having a constant throw and effective 65 throughout the entire throw to communicate turning movement to the platen, and means operative by turning the platen to vary the effect of said pawl and ratchet devices on said platen.

32. In a typewriting machine, the combination of a rotary platen, a line spacing 70 wheel, a carrier on which said wheel is rotatably supported, a friction roll normally engaged both by the platen and by said wheel, and means for adjusting said carrier comprising a device mounted on and movable by the platen axle, said device being 75 also operative to disconnect said wheel from said friction roll.

Signed at Philadelphia, in the county of Philadelphia, and State of Pennsylvania, 80 this 22 day of July A. D. 1914.

HERMANN V. FENGLER.
